COMPRESSOR SHUT-OFF VALVE
MECHANISM

Fred H. Stroup, Kirkwood, Mo., assignor to
Wagner Electric Corporation, St. Louis, Mo., a
corporation of Delaware

Application July 5, 1938, Serial No. 217,484

15 Claims. (CL 303—11)

My invention relates to valve mechanism and more particularly to valve mechanism for shutting off the intake of a compressor under certain conditions.

5 One of the objects of my invention is to provide a shutoff valve mechanism for a compressor which will automatically shut off the intake of the compressor when the pressure in a receiver thereof is a predetermined value and which is 10 so associated with the fluid pressure-actuated system connected to the receiver that the intake of the compressor will be reopened each time fluid under pressure is used from the receiver.

Another object of my invention is to provide 15 a shutoff valve mechanism which will positively close the compressor intake when the pressure in the receiver reaches the desired predetermined value and be held in closed position with sufficient force that there will be no leakage into the compressor and which will automatically positively open when the pressure in the receiver drops below a minimum value.

20 Another object of my invention is to so construct a shutoff valve mechanism and so associate the parts thereof that the mechanism will be simple in construction and efficient in operation.

Still other objects of my invention will become apparent from the following description 25 taken in connection with the accompanying drawings in which Figure 1 is a view showing how my novel valve mechanism is associated with the compressor, the receiver thereof and a fluid pressure-actuated system; and Figure 2 is 30 a longitudinal cross-sectional view of the valve mechanism showing the details thereof.

Referring to the drawing in detail, the air 35 compressor 1, with which I have illustrated my shut-off valve mechanism as being associated, is 40 of the rotary type having a stator 2 and an eccentrically mounted rotor 3 provided with a plurality of blades 4 (one only being shown). The stator has an intake port 5 and an outlet port 6, the latter opening into an oil dome 7 45 which is connected to a pressure tank 8 by means of a conduit 9; the oil dome and pressure tank both being considered as parts of the receiver of the compressor. The outlet of the compressor has associated therewith a check valve 10 for 50 preventing back flow of the compressed fluid and associated with the outlet of the dome is another check valve 11. The pressure tank 8 is shown as connected by a conduit 12 with a fluid motor 13 which may be employed to operate any mechanism desired, as for example, a braking mecha-

nism. The fluid pressure employed to actuate the fluid motor is controlled by a valve 14 in conduit 12, this valve being shown as a hand valve but it is understood that other valve mechanism such as a foot control valve may be employed if desired.

In compressors of the type described which are of well-known construction it is desirable to prevent the compressor from compressing fluid after the fluid in the receiver has been placed 10 under a predetermined maximum pressure. This is best accomplished by shutting off the intake port so that the air or other fluid which is being compressed is not permitted to enter the compressing chamber. It is also desirable that the 15 intake port not only be automatically closed at the proper time but that it also be reopened whenever the pressure in the receiver drops.

In accordance with my invention I have provided an improved valve mechanism 15 which 20 is associated with the compressor intake and also the compressor oil dome and the fluid pressure system whereby the desired opening and closing of the compressor intake is accomplished. The valve mechanism comprises a casing 16 having a stepped bore 17 forming two chambers 18 and 19 and a parallel stepped bore 20 forming two chambers 21 and 22. The chamber 21 communicates with an inlet port 23 and chamber 22 25 communicates with an outlet passage 24 which 30 is adapted to communicate with an intake port 5 of the compressor when the casing is mounted on the compressor. Between chambers 21 and 22 there is provided a valve seat 25 and cooperating with this seat to prevent communication between the two bores is a slidable valve member 35 30 positioned in chamber 21 and carrying a rubber element 27 for engaging the seat. The valve member is normally biased to open position by a spring 28 and when in this position the member 40 abuts the plug 29 which closes the open end of bore 20. The valve member carries a sealing cup 36 to prevent any passage of fluid past the valve member.

Within chamber 18 of bore 17 there is slidably 45 mounted a piston 31 which carries a projection 32 extending into chamber 19 and of such diameter as to provide a clearance space 33 between the projection and the wall of chamber 18. The portion of chamber 18 ahead of projection 32 50 30 has inset in its wall a ring member 34 so that its inner surface is flush with the surface of the chamber. This ring is formed with an annular groove 35 which communicates with a passage 36 leading from the left end of chamber 21 at 55

the rear of valve member 26. The groove is also in communication with chamber 18 by means of a slot 37 which is adapted to be controlled by a valve element in the form of a sealing cup 38 carried by the end of projection 32. The construction is such that when piston 31 is in a position wherein the sealing cup is to the right of slot 37, as shown in Figure 2, communication is permitted between chamber 18 and the chamber 10 at the rear of valve member 26 by way of passage 36. When the sealing cup is in this position, it prevents communication from chamber 18 to chamber 19 by way of clearance 33. When the piston is moved forwardly so the sealing element 38 is at the left of slot 37, communication is established between the chamber at the rear of valve member 26 and chamber 19 by way of passage 36, groove 35, slot 37, and clearance 33. Provision is also made by means 15 of a port 39 to connect chamber 19 at the left of piston 31 with the atmosphere. The left end of chamber 18 is in communication at all times with the dome of the compressor by means of conduit 40.

20 25 The piston 31 is provided with a sealing element 41 and chamber 19 at the right of the piston is connected by a passage 42 and a conduit 43 to conduit 12 at a point between control valve 14 and fluid motor 13. The piston 31 is normally biased by a spring 44 positioned between the piston and a plug 45 closing the right end of chamber 19. The plug also carries an 25 adjusting mechanism 46 for varying the tension of spring 44.

30 35 Spring 44 in the mechanism shown is so designed and adjusted to exert such a force on piston 31 that this piston will be moved to the left and maintained in this position as long as the pressure in the dome and also chamber 18 at the left of the sealing element 38 is less than one hundred pounds per square inch. When piston 31 is in its left-hand position all of the sealing element 38 will be positioned to the left of slot 37 and the chamber at the rear of valve member 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

in this chamber. The spring 28 will now be effective to move valve member 26 away from its seat and allow air to again pass to the compressor where it will be compressed and forced into the dome and the tank. When the pressure in the 5 dome and tank again reaches the value of one hundred pounds per square inch, valve member 26 will be reseated and the compressor shut off in the manner already described, it, of course, being assumed that the pressure acting on piston 10 15 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

As a result of leakage, the tank may lose considerable pressure if the fluid pressure-actuated motor is not operated for a long period of time. The valve mechanism disclosed, however, prevents the pressure in the tank from dropping below a predetermined minimum value. If the pressure in the dome should drop to a value of around ninety pounds per square inch, spring 44 will become effective to move piston 31 to the left against what pressure is in chamber 18 at 25 the left of the sealing element 38. When the sealing element is moved to its position at the left of slot 37, pressure in the chamber at the rear of the valve member 26 will be relieved, the valve member opened and the compressor permitted to operate to restore the one hundred pounds per square inch pressure in the dome and the receiver.

From the foregoing it is apparent that I have 35 provided a control system for a compressor that will automatically unload the compressor when the pressure in the receiver reaches a predetermined value and which will cause the compressor to again become operative to restore the pressure in the receiver whenever fluid under pressure 40 is used therefor. Provision is also made to prevent the pressure in the receiver from dropping below a given value notwithstanding the fluid under pressure may not be used therefrom.

Being aware of the possibility of modifications 45 in the particular structure herein described without departing from the fundamental principles of my invention, I do not intend that its scope be limited except as set forth by the appended claims.

Having fully described my invention, what I claim as new and desire to secure by Letters Patent of the United States is:

1. In apparatus of the class described, a fluid compressor provided with an intake port and an 55 exhaust port, a fluid pressure receiver connected to the exhaust port, a fluid pressure-actuated system adapted to be operated by fluid pressure from the receiver, means comprising valve mechanism for closing the intake of the compressor, 60 and means controlled by fluid pressure employed in the operation of the fluid pressure-actuated system for causing the intake of the compressor to be opened.

2. In apparatus of the class described, a fluid 65 compressor provided with an intake port and an exhaust port, a fluid pressure receiver connected to the exhaust port, a fluid pressure-actuated system adapted to be operated by fluid pressure from the receiver, valve mechanism associated 70 with the intake of the compressor, means for automatically operating the valve mechanism to close the intake by a predetermined pressure resulting from operation of the compressor, and means controlled by fluid pressure employed in 75

the operation of the fluid pressure-actuated system for causing the intake of the compressor to be opened.

3. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a movable valve member, resilient means for biasing the valve member to open position, means for moving said valve member to closed position by a predetermined fluid pressure, and means controlled by fluid pressure in the fluid pressure-actuated system for causing the movable valve member to assume open position.
4. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a movable valve member, resilient means for biasing the valve member to open position, means for moving said valve member to closed position when there is a predetermined fluid pressure in the receiver, and means operable by fluid pressure in the fluid pressure-actuated system for permitting the valve member to assume an open position under the action of the resilient means.
5. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, means for connecting the chamber to the exhaust side of the compressor whereby a predetermined pressure built up by the compressor will be effective to move the valve member to closed position, means forming an exhaust passage from the chamber, and piston valve means associated with the exhaust passage and operable by fluid pressure in the fluid pressure-actuated system for exhausting the chamber.
6. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, conduit means for connecting the chamber to the exhaust side of the compressor whereby a predetermined pressure built up by the compressor will be effective to move the valve member to closed position, means forming an exhaust passage from the chamber, valve means for disconnecting the chamber from the exhaust side of the compressor and connecting the chamber to its exhaust passage, and means for operating said valve means by fluid pressure in the fluid pressure-actuated system.
7. In apparatus of the class described, a fluid compressor provided with an intake port and an exhaust port, a fluid pressure receiver con-

nected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, a second chamber connected to the first chamber, conduit means for placing the second chamber in communication with the exhaust side of the compressor, conduit means for placing the second chamber in communication with the atmosphere, a slideable piston valve element in the second chamber for controlling communication between the first chamber and said conduit means, a spring for biasing the slideable element to a position where the first chamber communicates with the atmosphere, said slideable element being moved by a predetermined pressure to another position where the first chamber will be in communication with the exhaust side, and means operable by the fluid pressure employed in the fluid pressure-actuated system for moving said slideable element to the first named position.

8. In valve mechanism of the class described for association with the intake of a compressor and a fluid pressure receiver connected to the exhaust side thereof, a casing having a port for communication with the compressor intake, a movable member adapted to be acted upon by fluid pressure from the exhaust side of the compressor for closing the port, a spring for biasing the member to open position and preventing movement of the member to closed position except when acted upon by a predetermined pressure, means comprising a portion of the movable member and the casing for forming a chamber, means including a passage for connecting the chamber to atmosphere, a valve for controlling said passage, and means operable when the pressure in the receiver is a given value for closing said valve.

9. In valve mechanism of the class described for association with the intake of a compressor and a fluid pressure receiver connected to the exhaust side thereof, a casing having a port for communication with the compressor intake, a movable member adapted to be acted upon by fluid pressure from the exhaust side of the compressor for closing the port, a spring for biasing the member to open position and preventing movement of the member to closed position except when acted upon by a predetermined pressure, means comprising a portion of the movable member and the casing for forming a chamber, means including a passage for connecting the chamber to atmosphere, a valve for controlling said passage, and means for causing said valve to be opened when the pressure in the receiver drops a predetermined amount below the value of the predetermined pressure required to move the movable member.

10. In valve mechanism of the class described for association with the intake of a compressor and a fluid pressure receiver connected to the exhaust side thereof, a casing having a port for communication with the compressor intake, a movable member adapted to be acted upon by fluid pressure from the exhaust side of the compressor for closing the port, a spring for biasing the member to open position and preventing movement of the member to closed position except when acted upon by a predetermined pressure, means comprising a portion of the movable

- 5 member and the casing for forming a chamber, means including a passage for connecting the chamber to atmosphere, a valve for controlling said passage, and means for causing said valve to be closed when a predetermined pressure is built up in the receiver and to be opened when the pressure in the receiver drops to a value below said predetermined value.
- 10 11. In valve mechanism of the class described for association with a compressor and its receiver, a casing having a port for communication with the intake of the compressor, a movable valve member in said casing for controlling the port, a spring for biasing the member to open position, said member forming the movable wall of a chamber, means comprising a movable member for forming a second chamber adapted to be connected with the receiver, a spring acting on the movable member in the second chamber, a conduit connecting the chambers, a valve for controlling the conduit, and means operable by a predetermined fluid pressure in the second chamber for causing the movable member therein to move said valve to open position.
- 15 12. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, a second chamber having a port intermediate its ends in communication with the first chamber, conduit means for placing the second chamber in communication with the exhaust side 20 of the compressor, conduit means for placing the second chamber in communication with the atmosphere, a piston in said second chamber and a spring for biasing said piston to a position where the intermediate port will be on one side of the piston and in communication with the atmosphere only, said piston being moved by a predetermined pressure to another position where the intermediate port will be on the other side of the piston and in communication with the 25 exhaust side of the compressor.
- 25 13. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member 30
- 35 40
- 45
- 50
- 55
- therein for controlling the intake of the compressor, a spring for biasing the valve member to open position, conduit means for connecting the chamber to the exhaust side of the compressor, whereby a predetermined pressure built up by the compressor will be effective to move the valve member to closed position, means forming an exhaust passage from the chamber, piston valve means acted upon by fluid pressure in the receiver for alternately closing and opening the conduit means and the exhaust passage, and a spring for biasing said valve means to a position where the conduit means will be closed and the exhaust passage open, said spring permitting said valve means to open the conduit means and close the exhaust passage when the pressure built up by the compressor and acting on the piston valve means is a predetermined value.
14. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, 10 for biasing the element to a position where the conduit means will be closed and the exhaust passage open, said element being movable by a predetermined fluid pressure to another position where the conduit means will be open and the 15 exhaust passage closed.
15. In apparatus of the class described, a fluid compressor provided with an intake port and an exhaust port, a fluid pressure receiver connected to the exhaust port, a fluid pressure-actuated system adapted to be operated by fluid pressure from the receiver, valve mechanism associated with the intake of the compressor and comprising a chamber and a movable valve member therein for controlling the intake of the compressor, a spring for biasing the valve member to open position, a second chamber having a port intermediate its ends in communication with the first chamber, conduit means for placing the second chamber in communication with the exhaust side 20 of the compressor, conduit means for placing the second chamber in communication with the atmosphere, a piston in said second chamber and a spring for biasing said piston to a position where the intermediate port will be on one side of the piston and in communication with the atmosphere only, said piston being moved by a predetermined pressure to another position where the intermediate port will be on the other side of the piston and in communication with the 25 exhaust side of the compressor.
16. In apparatus of the class described, a fluid compressor provided with an intake port and an exhaust port, a fluid pressure receiver connected to the exhaust port, a fluid pressure-actuated system adapted to be operated by fluid pressure from the receiver, a casing having a passage in communication with the intake port, a chamber in the casing, a movable valve member in the chamber and adapted to control the passage, a spring for biasing the valve member to open position, conduit means for connecting the chamber to the receiver, means forming a relief passage from the chamber, and valve means operable by fluid pressure from the fluid-actuated system for causing a release of the fluid under pressure in the chamber.
